(57) **CLAIM**

The ornamental design for a shipping container, as shown and described.

DESCRIPTION

FIG. 1 is a perspective view of a shipping container showing my design;

FIG. 2 is a front view of the shipping container shown in FIG. 1;

FIG. 3 is a rear view of the shipping container shown in FIG. 1;

FIG. 4 is a side right view of the shipping container shown in FIG. 1;

FIG. 5 is a side left view of the shipping container shown in FIG. 1;

FIG. 6 is a top view of the shipping container shown in FIG. 1; and,

FIG. 7 is a bottom view of the shipping container shown in FIG. 1.

The dash-dash broken lines depict portions of the shipping container that form no part of the claimed design.

1 Claim, 7 Drawing Sheets
